[57] CLAIM

The ornamental design for an automated banking machine, as shown and described.

DESCRIPTION

FIG. 1 is a right front perspective view of an automated banking machine showing our new design, the left perspective view being a mirror image, the broken line showing of the mounting pedestal, screen and buttons is for illustrative purposes only and forms no part of the claimed design; FIG. 2 is a right side elevational view, the left side is a mirror image; and, FIG. 3 is a top plan view thereof, the bottom plan view is a mirror image.
